(57) **CLAIM**

I claim the ornamental design for a vehicle charge port, as shown and described.

DESCRIPTION

FIG. 1 is a front perspective view of a vehicle charge port. FIG. 2 is a front elevational view of the vehicle charge port depicted in FIG. 1.

FIG. 3 is a rear elevational view of the vehicle charge port depicted in FIG. 1.

FIG. 4 is a left side elevational view of the vehicle charge port depicted in FIG. 1.

FIG. 5 is a right side elevational view of the vehicle charge port depicted in FIG. 1.

FIG. 6 is a top plan view of the vehicle charge port depicted in FIG. 1.

FIG. 7 is a bottom plan view of the vehicle charge port depicted in FIG. 1; and,

FIG. 8 is a rear perspective view of the vehicle charge port depicted in FIG. 1.

The broken lines in the drawings illustrate portions of the vehicle charge port that form no part of the claimed design.
